UNITED STATES PATENT OFFICE.

ERWIN R. STOEKLE, OF MILWAUKEE, WISCONSIN, ASSIGNOR TO THE CUTLER-HAMMER MFG. CO., OF MILWAUKEE, WISCONSIN, A CORPORATION OF WISCONSIN.

THERMALLY-CONTROLLED CIRCUIT INTERRUPTER.

Application filed May 3, 1920. Serial No. 378,400.

To all whom it may concern:

Be it known that I, ERWIN R. STOEKLE, a citizen of the United States, residing at Milwaukee, in the county of Milwaukee and 5 State of Wisconsin, have invented new and useful Improvements in Thermally-Controlled Circuit Interrupters, of which the following is a full, clear, concise, and exact description, reference being had to the accompanying drawing, forming a part of this specification.

This invention relates to thermally controlled circuit interrupters.

More particularly the invention relates 15 to circuit interrupters of the type disclosed and claimed in my co-pending application, Serial No. 358,601, filed February 14, 1920, such type of circuit interrupter comprising a container, preferably glass, and a conductor therein which is fluid at working temperatures, and adapted under thermic influence to be subjected to action of a fluid under pressure for effecting electrical discontinuity thereof.

25 The present invention has among its objects to provide a simple, rugged and durable embodiment of such circuit interrupter which may be advantageously used for various purposes and especially as an overload circuit breaker.

Another object is to provide a circuit interrupter of the aforesaid type with associated means to influence the responsiveness thereof within a given range of the controlling thermic changes.

Another object is to provide a circuit breaker of the aforesaid character with associated means to differently influence the responsiveness thereof within different 10 ranges of the controlling thermic changes to render the same of the inverse time element type.

Another object is to provide a self contained circuit interrupter of the aforesaid type wherein the parts are particularly designed to promote standardization thereof and of the parts to be associated therewith and wherein the parts are designed for ready calibration.

50 Another object is that of providing a circuit interrupter of the aforesaid type having its individual elements constructed and arranged to facilitate assembly and installa-

tion and also repair and replacement when necessary.

Other objects and advantages will hereinafter appear.

In the accompanying drawing, wherein is illustrated an embodiment of the invention, Figure 1 is a vertical sectional illustration 80 thereof;

Figure 2 is a front elevational view thereof; while,

Figure 3 is a bottom plan view, partly in section, of the same.

Referring to the drawing, the same illustrates a thermally responsive circuit control element 5, a heating coil 6 arranged to surround an intermediate portion of said element and a thermally and electrically insulating support 7 for said element and said coil, said support being mounted upon a suitable insulating panel 8.

The circuit control element 5 is preferably of the type disclosed and claimed in my co-pending application aforementioned, and includes a hermetically tight container composed of insulating material and comprising an enlarged bulb 9 having an axially aligned and restricted tubular extension 10 therebelow. Electrodes 11 and 12 are sealed within the outer ends of said bulb and said extension respectively and arranged to penetrate material distances toward one another within the container. Said electrodes are normally electrically connected by a quantity of mercury 13 or other vaporizable liquid conductor which fills said extension and rises an appreciable distance within the bulb.

The remaining space within the container 90 is preferably evacuated to reduce the hydrostatic pressure upon the mercury column and also to remove any gaseous matter which might react unfavorably upon the exposed conductive parts during operation. However, such space might optionally be filled with an electrically inert and non-oxidizing gas whereas hermetic closure of such space is not essential.

Said tubular extension is provided with an interiorly enlarged portion 14 preferably located at a material distance below the bulb 9 and adapted to include an increased bulk of mercury. Upon a predetermined rise in temperature of said bulk of mercury, as by 100 passage through the heating coil 6 of cur-

rent in excess of a predetermined value, said mercury becomes vaporized whereupon the consequent expansion of the liberated vapor serves to drive the liquid mercury located 5 thereabove out of the intermediate portion of the tubular extension 10 and into the bulb 9 thereby interrupting the electrical continuity of the mercury column and thus interrupting circuit between the electrodes 11 10 and 12.

The inner diameter of the tubular extension is so restricted that the capillary action 15 between the liquid mercury and the sides of said passage is sufficient to prevent re-flux of the liquid mercury within said extension and consequent restoration of electrical continuity of the column so long as a predetermined vapor pressure persists within the enlarged portion 14 of the passage. However, upon a predetermined cooling of the 20 vapor within such intermediate chamber the weight of the mercury column located thereabove is sufficient to overcome both the capillary action and the vapor pressure, whereupon 25 liquid mercury flows back within the tubular extension and reunites with the mercury which remains in the lower portion of said extension for re-establishment of the interrupted circuit. In practice the upper 30 electrode 11 is preferably offset laterally out of alignment with the axis of the tubular extension 10 thereby eliminating or substantially reducing the tendency toward the formation of an arc during the afore-described 35 circuit interruption.

The support 7 is substantially of bilaterally symmetrical contour and in general cylindrical, being divided along a vertical plane into similar and interchangeable sections 40 15 and 16, having adjacent faces adapted to abut one another accurately throughout a major portion of their common extent and being in practice rigidly clamped together. The assembled support is axially 45 provided with a multi-diameter bore extending therethrough and adapted to contain and support the circuit control element 5 and the heating coil 6 in suitable operative relation to one another, said bore appearing in the 50 separate support section as a pair of registering semi-circular grooves of varying diameter.

The upper portion of the bore is relatively 55 large to receive the enlarged bulb 9 of the element 5 and is provided with an annular shoulder 17 to co-operate with the lower portion of said bulb for direct support of said element. The portion of said bore below said shoulder is restricted to conform 60 approximately to the size of the tubular extension 10 located therein. However, said restricted portion of the bore is again enlarged at a point below said shoulder 17 to provide a space to contain said heating coil 65 6, said second enlarged portion being pro-

vided with upper and lower annular shoulders 18 and 19 for supporting and maintaining said coil in suitable relation to the enlarged portion 14 of said passage. The portion of said bore located below the said shoulder 19 is again restricted to conform approximately to the diameter of the tubular extension.

The support 7 is medially provided with a pair of parallel passages 20 and 21 extending at right-angles to the axis of the support and displaced laterally from said axis, being preferably located in the same horizontal plane, portions of said passages being included in each of the support sections. Said passages are adapted to receive a pair of elongated clamping studs 24 and 25 having suitably located clamping nuts for securing the sections of the support in assembled relation, said studs also providing for securement of the assembled support upon the panel 8 in a relation of two point suspension.

Each of said support sections is further provided with a pair of counter-bored passages 26 and 27, located adjacent its upper and lower extremities respectively and extending radially thereof, said passages of the section 15 being adapted to receive upper and lower terminal bolts 28 and 29, the panel 8 having enlarged openings to receive the projecting ends of said bolts together with their clamping and terminal nuts.

Each section of the support is exteriorly provided with a flat flush surface 30 extending about and between the spaced radial passages 26 and 27 thereof, and is further provided with enlarged portions 31 and 32 located adjacent the medially located passages 20 and 21 thereof; said enlarged portions serving both to increase the strength of the respective sections at such points and also to provide flat surfaces normal to the axes of said latter passages but located below the plane of the respective flush surfaces 30 thus providing a space to receive the clamping nuts of the studs 24 and 25 within the contour of such flush surfaces.

Each of said support sections is furthermore provided with a pair of reduced passages 33 and 34 extending in general parallel with the passages 20 and 21, aforescribed and located adjacent the shoulders 19 and 18 respectively to receive the respective terminal portions of the heating coil 6 and conduct the same outside the support. Said terminal portions are in practice preferably bent about the respective clamping studs 24 and 25, the latter being thus adapted to act as terminals for the heating coil.

In practice the respective upper and lower ends of the unit 5 are provided with end caps 35 and 36 preferably cemented thereto, and adapted to fit snugly within the respective upper and lower ends of the bore with-

in the support. The outer ends of the respective electrodes 11 and 12 are permanently and electrically connected with the respective end caps whereby the latter serve 5 jointly as positioning and terminal devices for the element 5, while also affording mechanical protection thereto. Conductive clips 37 and 38 are clamped upon the respective terminal bolts 28 and 29 for electrically connecting the latter with the respective end caps 35 and 36, the end portions 10 of the support being provided with suitable recesses to receive the respective clips.

By the foregoing arrangement the heating coil 6 is maintained in suitable operative relation to the element 5 and particularly to those portions of said element to be directly influenced thereby, whereas both said coil and said element are entirely surrounded 20 radially by the support 7.

The aforescribed arrangement is advantageous in securing the desired inverse time element of the device whereby the same is adapted to respond with varying degrees of 25 dispatch to varying conditions of energizing of the heating coil. Thus, during moderate overloads of the circuit including said coil, the corresponding values of heat developed thereby are dissipated to the surrounding 30 media chiefly by conduction and only to a relatively slight extent by radiation. Hence assuming said coil to be in mechanical contact with the support 7 but spaced from the tubular extension 10 a relatively large proportion 35 of the heat developed will be absorbed by the support whereas a relatively small value of such heat will be applied to the element 5, whereby response of said element for interruption of circuit may be delayed for a relatively long period.

On the other hand assuming such an overload of the circuit including the heating coil as to heat the latter to a comparatively high temperature, a relatively high proportion of 45 the heat developed is radiated directly to the element 5 for effecting an earlier response thereof for interruption of the circuit, a relatively small value of the heat being under these conditions absorbed by the support, whereas the latter serves to some 50 extent to direct the radiations toward the extension. The support thus serves both to prolong the time element for moderate overloads and to shorten such time element for 55 heavier overloads.

Also assuming the circuit of the heating coil to be controllable by the switch element 5, following interruption of such circuit by said element under any of the aforeslated 60 conditions the support 7 may be arranged to retain the heat developed by said coil for a relatively long period whereby re-establishment of the interrupted circuit may be correspondingly delayed.

65 All of the aforescribed operative char-

acteristics of the device may be varied or calibrated in numerous ways, as by varying the contour and dimensions of the control element 5 particularly the inner diameter of its restricted passage and of the enlarged 70 portion of such passage to be directly subjected to the action of the heating coil. Also through variation of the electro-thermic characteristic of the heating coil, or optionally by varying the radial distance of said 75 coil from the tubular extension or from the support either with or without interposition of media for varying the conducting and radiating conditions, the character of the response of the device to varying electro-thermic 80 conditions may be regulated throughout exceedingly wide ranges.

Owing to the unreticulated contour of the control element 5 and to the aforescribed manner of co-operation thereof with the support 7, it is obvious that the former may be readily removed and replaced with reference to the latter without disassembly of the latter by merely springing back the clip 37, the upper side portions of the support 90 being preferably cut away as indicated at 39 for facilitating such action.

The heating coil 6 is moreover readily accessible upon removal of only the front section of the support. Whereas for removal 95 of the heating coil or inspection of the terminals thereof, the rearwardly located support section may also be readily slipped forwardly from the studs 24 and 25.

Obviously the aforescribed sectional construction of the support is not absolutely essential herein since the non-embedded and radially removable arrangement of the heater coil 6 is likewise not essential, whereas, assuming the heater coil to be non-embedded in the support as illustrated, should it be desired to provide a different character of removability of the coil from the support, whether the latter be constructed sectional as illustrated or otherwise, the herein disclosed manner of mounting and assembly of the control element 5 with reference to said support will be at once suggestive to one skilled in the art of ways whereby such result may be attained.

In practice the flush surface 30 of the front support section is preferably covered by a suitable face plate 40 secured thereto by means of short screw bolts 41, extending through and closing the passages 26 and 27 thereof, such plate serving to cover the openings of the reduced passages 33 and 34 in said section and lending a neat and finished appearance to the device.

What I claim as new and desire to secure by Letters Patent is:

1. In a circuit interrupter the combination with a control element comprising a container and a conductor therein which is fluid at working temperature and a heater 130

adapted to subject said conductor to action of a fluid under pressure for effecting electrical discontinuity thereof, of means for delaying response of said element within a 5 given range of variations of such influence.

2. In a circuit interrupter the combination with a control element comprising a container and a conductor therein which is fluid at working temperature and thermal 10 means extraneous to said conductor for subjecting the latter to action of a fluid under pressure for rendering said conductor electrically discontinuous, of means for hastening response of said element within given 15 range of variation of such influence.

3. In a circuit interrupter the combination with a control element comprising a container and a conductor therein which is fluid at working temperature and thermal 20 means extraneous to said conductor to subject the latter to action of a fluid under pressure for rendering said conductor electrically discontinuous, of means adapted within different ranges of variation of such 25 influence to respectively delay and hasten response of said element.

4. In a circuit interrupter, the combination with a control element comprising a container and a conductor therein which is fluid at working temperatures and adapted 30 under thermic influence to be subjected to action of a fluid under pressure for rendering the same electrically discontinuous, of associated means adapted to undergo thermic 35 changes for subjecting said element to such influence and means for delaying response of said element within a given range of thermic changes of said former means.

5. In a circuit interrupter, the combination with a control element comprising a container and a conductor therein which is fluid at working temperatures and adapted under thermic influence to be subjected to 40 action of a fluid under pressure for rendering the same electrically discontinuous, of associated means adapted to undergo thermic 45 changes for subjecting said element to such influence and means for hastening response of said element within a given range 50 of thermic changes of said former means.

6. In a circuit interrupter, the combination, with a control element comprising a container and a conductor therein which is fluid at working temperatures and adapted 55 under thermic influence to be subjected to action of a fluid under pressure for rendering the same electrically discontinuous, of associated means adapted to undergo thermic 60 changes for subjecting said element to such influence and means for delaying response of said element within a given range of thermic changes of said former means and for hastening response of said element within a different range of thermic changes of 65 said former means.

7. In a circuit interrupter, the combination with a control element comprising a container and a conductor therein which is fluid at working temperatures and adapted under thermic influence to be subjected to 70 action of a fluid under pressure for rendering the same electrically discontinuous, of associated means adapted to undergo thermic changes for subjecting said element to such influence and heat absorbing means associated with said former means to vary the degree or influence of said former means upon said element.

8. In a circuit interrupter, the combination with a control element comprising a 80 container and a conductor therein which is fluid at working temperatures and adapted under thermic influence to be subjected to action of a fluid under pressure for rendering the same electrically discontinuous, of 85 associated means adapted to undergo thermic changes for subjecting said element to such influence and a heat absorbing support for said element and said associated means, for varying the responsiveness of the former under different thermic conditions of the 90 latter.

9. In a circuit interrupter, the combination with a control element comprising a container and a conductor therein which is fluid at working temperatures and adapted under thermic influence to be subjected to action of a fluid under pressure for rendering the same electrically discontinuous, of 95 associated means adapted to undergo thermic changes for subjecting said element to such influence and a heat absorbing support for said element and said associated means, adapted to absorb different proportions of the heat of said associated means 100 under different thermic conditions of the latter for varying the degree of influence of said means upon said element.

10. In a circuit interrupter, the combination with a control element comprising a 11 container and a conductor therein which is fluid at working temperatures and adapted under thermic influence to be subjected to action of a fluid under pressure for rendering the same electrically discontinuous, of a 12 heating element for subjecting said element to such influence and supporting means for said elements adapted to absorb different proportions of the heat developed by said heating element under different thermic 11 conditions of the latter.

11. In a circuit interrupter, the combination with a control element comprising a container and a conductor therein which is fluid at working temperatures and adapted 12 under thermic influence to be subjected to action of a fluid under pressure for rendering the same electrically discontinuous, of a resistor for subjecting said element to such influence and heat absorbing supporting 13

means for said element and said resistor adapted to absorb different proportionate values of the heat developed by said resistor under different conditions of energization 5 of the latter.

12. In a circuit interrupter, the combination with a control element comprising a container and a conductor therein which is liquid at working temperatures and adapted 10 under thermic influence to be subjected to action of a fluid under pressure for effecting electrical discontinuity thereof, of means for subjecting said element to such influence and common means for independently supporting said element and said former means in co-operative relation to one another. 15

13. In a circuit interrupter, the combination with a control element comprising a container having a restricted tubular extension and a conductor which is liquid at working temperatures filling said extension and adapted under thermic influence to be rendered electrically discontinuous, of a 20 heating coil surrounding said extension for so influencing the conductor contained therein and joint supporting means for said element and said coil comprising a body of heat absorbing material surrounding said coil and said extension to absorb different 25 proportionate values of the heat developed by said coil dependent upon the degree of 30 energization of the latter.

14. The combination with an insulating support having an opening therein of a 35 control element readily insertable within said opening and removable therefrom and terminal means for said element, said element comprising a container and a conductor therein which is liquid at working 40 temperatures and adapted under thermic influence to be subjected to action of its own vapor under pressure for effecting electrical discontinuity thereof.

15. The combination with an insulating support having an opening therein of a control element readily insertable within said opening and removable therefrom, said element comprising a container and a conductor therein which is liquid at working 45 temperatures and adapted under thermic influence to be subjected to action of its own vapor under pressure for effecting electrical discontinuity thereof, means for so influencing said conductor and terminal means for said 50 element carried by said support.

16. The combination with a control element comprising an insulating container having a restricted tubular extension and a conductor which is liquid at working 55 temperatures located within said extension and adapted under thermic influence to be rendered electrically discontinuous, electrodes carried by said container and in electrical

connection with the conductor contained therein, conductive members carried exteriorly of said container and in electrical connection with said electrodes, terminal devices carried by said support and conductive clips for connecting said terminal devices with the respective exteriorly located 65 conductive elements of said unit, said clips serving for positioning and retention of said element within said support and means for subjecting said element to thermic influence for interrupting the electrical connection 70 between said terminal devices. 75

17. The combination with a control element comprising a container and a conductor therein which is liquid at working temperatures and adapted under thermic influence to be subject to action of its own vapor under pressure for effecting electrical discontinuity thereof of a support for said element having an opening for ready insertion and removal of said element, said support 80 comprising separable and interchangeable sections and common means for clamping said sections in assembled relation and for mounting said support upon a suitable base. 85

18. In a circuit interrupter, the combination with a control element comprising a container and a conductor therein which is fluid at working temperature and adapted under thermic influence to be subjected to action of a fluid under pressure for effecting, 90 selectively, interruption and restoration of electrical continuity of said conductor, of means for delaying response of said element within a given range of variation of such influence. 95

19. In a circuit interrupter, the combination with a control element comprising a container and a conductor therein which is fluid at working temperature and adapted under thermic influence to be subjected to action of a fluid under pressure for effecting, 100 selectively, interruption and restoration of electrical continuity of said conductor, of means for delaying response of said element, both for interruption and for restoration of continuity, within given ranges of 105 variation of such influence. 110

20. In a circuit interrupter, the combination with a control element comprising a container and a conductor therein which is fluid at working temperature and adapted under thermic influence to be subjected to action of a fluid pressure of its own vapor for effecting, selectively, interruption and restoration of electrical continuity of said conductor, of means for delaying response of said element within a given range of variation of such influence. 115

In witness whereof, I have hereunto subscribed my name.

ERWIN R. STOEKLE.
